CLAIM

The ornamental design for a square eyeglass lens with horizontal ovular aperture, as shown and described.

DESCRIPTION

FIG. 1 is a front environmental view of a square eyeglass lens with horizontal ovular aperture showing my new design;
FIG. 2 is a front perspective view of the square eyeglass lens with horizontal ovular aperture;
FIG. 3 is a front view thereof;
FIG. 4 is a rear view thereof;
FIG. 5 is a right side view thereof with a left side being a mirror image; and,
FIG. 6 is a top view thereof with a bottom view being a mirror image.
The broken lines are included for illustrative purposes only and form no part of the claimed design.
